(57) **CLAIM**

The ornamental design for a head gear sleeve, as shown and described.

DESCRIPTION

FIG. 1 is a perspective view of an embodiment of a head gear sleeve in accordance with our new design.

FIG. 2 is a top plan view thereof.

FIG. 3 is a bottom plan view thereof.

FIG. 4 is a front view thereof.

FIG. 5 is a rear view thereof.

FIG. 6 is a first side view thereof.

FIG. 7 is a second side view thereof.

FIG. 8 is a perspective view of the head gear sleeve of FIG. 1 presented on exemplary head gear having a chin cup.

FIG. 9 is a perspective view of a head gear sleeve in accordance with our new design.

FIG. 10 is a top plan view thereof.

FIG. 11 is a bottom plan view thereof.

FIG. 12 is a front view thereof.

FIG. 13 is a rear view thereof.

FIG. 14 is a first side view thereof.

FIG. 15 is a second side view thereof.

FIG. 16 is a perspective view of the head gear sleeve of FIG. 9 presented on exemplary head gear having a chin cup; and, FIG. 17 is a perspective view of the head gear sleeve of FIG. 9 in a partial separated configuration along its longitudinal axis.

The broken lines shown in the drawings illustrate environmental structure of the head gear sleeve and form no part of the claimed design. The head gear sleeve of the aforementioned Figures is a combination of tubular knitted fabric. In addition, the surface shading, if any, illustrated in the drawings is provided merely to highlight the contour of the design, it is not intended to be illustrative of texture or gloss.
